United States Patent Office

Des. 208,217

Patented Aug. 1, 1967

208,217

ARTICLE HOLDER FOR MOTOR VEHICLES

Thomas F. Castloo, 316 E. Broad,
Mineola, Tex. 75773

Filed Jan. 14, 1966, Ser. No. 606

Term of patent 14 years

(Cl. D58—13)

FIG. 1

FIG. 2

FIG. 3

FIG. 4

FIG. 5

FIG. 1 is a perspective view of an article holder for motor vehicles showing my new design;

FIG. 2 is a top plan view;

FIG. 3 is a side elevational view;

FIG. 4 is an end elevational view; and

FIG. 5 is an end elevational view showing the end opposite that seen in FIG. 4.

The side of the litter holder opposite the side shown in FIG. 3 is identical to the side as shown in FIG. 3.

I claim:

The ornamental design for an article holder for motor vehicles, as shown and described.
